PHASE MODULATOR

Murray G. Crosby, Riverhead, N. Y., assignor to
Radio Corporation of America, a corporation of
Delaware

Application October 27, 1938, Serial No. 237,175

7 Claims. (Cl. 179—171.5)

This application concerns a new and improved phase modulator of the type in which two phase differentiated voltages of carrier wave frequency are relatively amplitude modulated and combined to produce a resultant which varies in phase. In one modification only one of the two voltages of carrier wave frequency is modulated and the phase and amplitude relations of the modulated voltage and unmodulated voltage are given for linear modulation. In a second modification, frequency multiplication is introduced following the phase shifting so that the phase difference is multiplied by the order of the multiplication and smaller initial phase difference is required.

In the prior art of this type of phase modulator, the carrier voltage is divided into two phase shifted branches which are differentially amplitude modulated and recombined at the same frequency. This type of phase modulator is described in my United States application #588,309, filed January 23, 1932, now Patent #2,081,577 dated May 25, 1937, and my United States application #616,803, filed June 13, 1932, now Patent #2,065,656 dated December 29, 1936. As will be shown in the mathematical analysis which follows, this differential modulation requires a phase difference of 90 degrees between the two carrier voltages of equal amplitude to produce the most linear modulation. By the same mathematical method, I have found that it is possible to produce the same quality and degree of modulation for the case where only one of the carrier voltages is modulated. This is accomplished by setting the carrier voltages 135 degrees apart in phase and adjusting the amplitudes of the two carrier voltages so that the modulated carrier is equal to 0.707 times the unmodulated carrier. Thus by properly adjusting the single modulator system, the performance of the double modulator system can be equalled for all practical purposes.

In describing my invention in detail, reference will be made to the attached drawings, wherein:

Figure 1 illustrates by block diagram a phase modulator wherein carrier wave voltages of equal amplitude are displaced in phase and differentially modulated in amplitude to produce outputs which are combined;

Figure 2 illustrates diagrammatically a phase modulator arranged in accordance with the present invention. In this phase modulator the carrier wave voltages which are of different amplitude are displaced in phase and one of them only is modulated in amplitude. The outputs are then

combined to obtain a phase modulated resultant.

Figures 3 and 4 illustrate schematically the circuit connections of two modifications of phase modulators, as illustrated in Figure 2; while,

Figure 5 illustrates schematically the circuit elements of a new and improved phase modulator as illustrated in Figure 1.

Figure 1 shows a block diagram of the differential type of phase modulator. The carrier voltage from 1 is fed through phase adjuster 2 to modulator 3 and directly from 1 to modulator 4. Differential amplitude modulation is applied to modulators 3 and 4 so that 3 is modulated up at the time 4 is modulated down. These two modulated outputs are combined to produce a resultant output which varies in phase between the limits imposed by the phase difference between the two carrier voltages fed to 3 and 4. The following two amplitude modulated waves are combined:

$$e_1 = E_1(1+M \sin pt) \sin \omega t \quad (1)$$

$$e_2 = E_2(1-M \sin pt) \sin (\omega t + \beta) \quad (2)$$

where M is the percentage of amplitude modulation on the two modulators, $p=2\pi$ times the modulating frequency, $\omega=2\pi$ times the carrier frequency, and β = the phase difference between the two carrier voltages. Combining (1) and (2) vectorially gives:

$$e = \sqrt{E_1^2(1+M \sin pt)^2 + E_2^2(1-M \sin pt)^2 + }$$

$$2E_1E_2(1+M \sin pt)(1-M \sin pt) \cos \beta$$

$$\sin \left[\omega t + \tan^{-1} \frac{E_1(1+M \sin pt)}{E_2(1-M \sin pt)} \right] \quad (3)$$

By adjusting the two carrier voltages equal ($E_1=E_2=E$) and setting them at the optimum phase difference of 90 degrees ($\beta=90$ degrees), (3) reduces to:

$$e = \sqrt{2E\sqrt{1+M^2 \sin^2 pt} \sin \left\{ \omega t + \tan^{-1} \frac{(1-M \sin pt)}{(1+M \sin pt)} \right\}} \quad (4)$$

By applying the binomial theorem and the relation

$$\tan^{-1} X = -\tan^{-1} \left[\frac{1-X}{1+X} \right] + 45^\circ$$

(4) simplifies to:

$$e = \sqrt{2E} \left(1 + \frac{M^2}{2} \sin^2 pt - \frac{M^4}{8} \sin^4 pt + \frac{M^6}{16} \sin^6 pt - \dots \right)$$

$$\sin \{ \omega t + 45^\circ - \tan^{-1} M \sin pt \} \quad (5)$$

Expanding the arc-tangent, term of (5) into

its series and substituting multiple angle functions for the exponential functions gives:

$$\begin{aligned}
 e &= 2\sqrt{E} \left[\left(1 + \frac{M^2}{4} - \frac{3M^4}{64} + \frac{5M^6}{256} - \dots \right) - \right. \\
 &\quad \left. \frac{Y}{\left(\frac{M^2}{4} + \frac{M^4}{16} + \frac{15M^6}{512} + \dots \right)} \cos 2pt - \right. \\
 &\quad \left. \frac{X}{\left(\frac{M^4}{64} - \frac{3M^6}{256} \dots \right)} \cos 4pt - \frac{W}{\left(\frac{M^6}{512} \dots \right)} \cos 6pt. \dots \right] \\
 &\quad \sin \{\omega t + 45^\circ - \} \\
 &\quad \left. \begin{aligned}
 &\quad \left(M - \frac{M^3}{4} + \frac{M^5}{8} - \frac{5M^7}{64} + \frac{7M^9}{128} - \frac{21M^{11}}{512} + \dots \right) \sin pt - \\
 &\quad \left(\frac{M^3}{12} - \frac{M^5}{16} + \frac{3M^7}{64} - \frac{7M^9}{192} + \frac{15M^{11}}{512} - \frac{99M^{13}}{4096} + \dots \right) \sin 3pt + \\
 &\quad \left(\frac{M^5}{80} - \frac{M^7}{64} + \frac{M^9}{64} - \frac{15M^{11}}{1024} + \frac{55M^{13}}{4096} - \dots \right) \sin 5pt - \\
 &\quad \left. \left(\frac{M^7}{448} - \frac{M^9}{256} + \frac{5M^{11}}{1024} - \frac{11M^{13}}{2048} + \dots \right) \sin 7pt + \dots \right\} \quad (6)
 \end{aligned} \right]
 \end{aligned}$$

Equation 6 may be rewritten:

$$\begin{aligned}
 e &= \sqrt{2EZ} \left[\left(1 - \frac{Y}{Z} \cos 2pt - \frac{X}{Z} \cos 4pt - \frac{W}{Z} \cos 6pt \dots \right) \right. \\
 &\quad \left. \sin \{\omega t + 45^\circ - A \sin pt - B \sin 3pt + \right. \\
 &\quad \left. C \sin 5pt - D \sin 7pt + \dots \right] \quad (7)
 \end{aligned}$$

Thus the wave is amplitude modulated with even harmonics having percentages of modulation equal to Y/Z , X/Z etc. The phase modulation produced consists of fundamental and only odd harmonics. The percentage third harmonic is equal to $B/A \times 100$, the fifth equal to $C/A \times 100$, etc.

The circuit of Figure 2 shows the arrangement of the modulator in which only one of the phase differentiated voltages is modulated. The carrier source is fed directly through amplifier 12 to the output and through phase shifter 11 to amplifier modulator 13 from which output is taken to combine with the output of amplifier 12. Only amplifier modulator 13 is modulated in amplitude—12 is an amplifier or coupling tube which serves as a one-way device to prevent modulator 13 from singing. In this case the following two voltages are to be combined:

$$e_1 = E_1(1 + M \sin pt) \sin(\omega t + \beta) \quad (8)$$

$$e_2 = E_2 \sin \omega t \quad (9)$$

The vectorial combination produces the following resultant:

$$\begin{aligned}
 e &= \sqrt{E_1^2(1 + M \sin pt)^2 + E_2^2 + 2E_1E_2(1 + M \sin pt) \cos \beta} \\
 &\quad \sin \left\{ \omega t + \tan^{-1} \frac{\sin \beta}{E_1(1 + M \sin pt) + \cos \beta} \right\} \quad (10)
 \end{aligned}$$

The optimum conditions are obtained when $\beta = 135$ degrees and

$$\frac{E_1}{E_2} = 0.707$$

Then

$$\begin{aligned}
 e &= 0.707 E_2 \sqrt{1 + M^2 \sin^2 pt} \sin \{\omega t + \tan^{-1} \frac{0.707}{0.707(1 + M \sin pt) - 0.707}\} \quad (11)
 \end{aligned}$$

$$= 0.707 E_2 \sqrt{1 + M^2 \sin^2 pt} \sin \left\{ \omega t + \tan^{-1} \frac{1}{M \sin pt} \right\} \quad (12)$$

$$\begin{aligned}
 e &= 0.707 E_2 \left(1 + \frac{M^2}{2} \sin^2 pt - \frac{M^4}{8} \sin^4 pt + \right. \\
 &\quad \left. \frac{M^6}{16} \sin^6 pt - \dots \right) \\
 &\quad \sin \{\omega t + 90^\circ - \tan^{-1} M \sin pt\} \quad (13)
 \end{aligned}$$

Equation 13 is identical in form to 5 which is reducible to 6 and 7. Thus the two types of modulators produce the same degree of undesired amplitude modulation and the same degree and quality of phase modulation for a given degree of amplitude modulation. Since the single modulator type of circuit is simpler, an advantage is gained without the addition of disadvantages.

When the modulators 3 and 4 of Figure 1 and amplifier and modulator 12 and 13 of Figure 2 are operated as frequency multipliers, the phase difference between the two carrier voltages is multiplied by the order of the frequency multiplication. Thus, in the case of frequency doubling, for the double modulator type of circuit shown in Figure 1, the phase difference effected by 2 would be adjusted to 45 or 135 degrees so that when this phase difference is multiplied in the modulators the resulting phase difference would be 90 or 270 degrees. The modulators perform the dual function of varying the amplitude in accordance with the signal wave and multiplying the frequency. Such a modulator would consist of a modulator tube having its input tuned to the carrier source frequency and its output tuned to the desired harmonic which would be the second in this example of frequency doubling. If desired, the two processes of frequency multiplying and modulating may be separated in units 3 and 4 so that an ordinary modulator tube is cascaded with a frequency multiplier tube. The result would be the same as though both functions were accomplished in the same tube. Differential modulation is applied to modulators 3 and 4 by means of push-pull transformer 5 which is arranged to modulate one of the modulators up at the instant the other is being modulated down. The two modulated outputs are combined in a common plate circuit of the modulators in 3 and 4 or in the last stage of the cascaded frequency multipliers and modulators in 3 and 4.

For the single modulator case of Figure 2, for the same example of frequency doubling, the phase difference effected by 11 would be 67.5 or 112.5 degrees so that when multiplied the difference would be 135 or 225 degrees. In this circuit amplifier 12 forms the single function of frequency multiplying whereas 13 is modulated by the signal while also performing the function of frequency multiplication. Combination of the two outputs would be effected in the common plate circuits of 12 and 13 or 12 and the last stage of 13. This will be understood when it is remembered that frequency multiplication multiplies frequency or phase deviations. This is the case of a phase difference which would be the same as a phase deviation.

75 The insertion of the frequency multiplication

may precede the modulators or succeed them, but it must precede the combination point in order to accomplish the function of reducing the required phase difference between the carriers.

The circuit of Figure 3 shows a specific embodiment of the type of phase modulator in which one of two phase differentiated carrier voltages is modulated and combined with the other. Carrier source 100 feeds tuned circuit 101 which is tuned to the carrier frequency. R and C form a phase shifter to effect a phase shift in conjunction with the 180 degree shift of push-pull tuned circuit 101 so that the voltages of carrier wave frequency fed to grids G₁ and G₂ of amplifier 103 and modulator 102 are 135 degrees apart which is the optimum phase adjustment for this type of modulator. Phase shifter R, C also effects an amplitude reduction which is made such that the amplitude of the voltage of carrier wave frequency fed to the modulated tube 102 is 0.707 times that fed to the unmodulated tube 103. The combined voltages appear in tuned circuit 104 which is connected to plates 109 and 110 and is tuned to the carrier frequency. In the embodiment shown the modulator tube 102 is suppressor-grid modulated by potentials fed to jack 107 and thence to the primary winding P of transformer 106, the secondary S of which is connected to the suppressor grid 111 of tube 102.

The circuit of Figure 4 shows a specific embodiment of the type of phase modulator in which the modulator and amplifier tubes are frequency multipliers. Wave energy of carrier wave frequency is furnished from an electron discharge tube oscillator of the constant frequency type comprising a crystal PC connected with a control electrode of a tube 200 having a tuned reactive circuit 203 connected with its anode 205. The oscillations produced are fed by a phase shifter R, C to the grid G₁ of modulated frequency multiplier tube 201 and through amplitude regulating condenser C₁ to the control grid G₂ of frequency multiplier tube 202. Without frequency multiplication a 135 degree phase separation between the carrier voltages is required, but for the case of frequency doubling a 67.5 degree phase shift would be used preceding the doublers. Thus R, C is adjusted for 67.5 degrees shift. C₁ allows an amplitude adjustment of the carrier voltage supplied to tube 202 to be made to compensate for the loss in the phase shifter R, C and to obtain the required voltage relationship of 0.707:1 between the multiplied outputs of the modulated and unmodulated stages 201 and 202, respectively. The modulated tube uses suppressor-grid modulation the same as in Figure 2. Tuned circuit 204 would be tuned to the desired harmonic of the carrier frequency.

Figure 5 shows how frequency multiplication may be applied to the differential type of modulator in which both frequency multiplier stages are modulated. For the case of frequency doubling in which 304 is tuned to twice the frequency of the carrier wave from 303, phase shifter R, C would be adjusted to shift 45 degrees and the amplitudes of the two voltages could be balanced with condenser C₁. The modulators are suppressor-grid modulated by modulating potentials applied to the primary winding P of push-pull transformer 306, which has its secondary winding S connected to suppressor grids 311 and 315. For the example of frequency doubling, with the voltages to G₁ and G₂ set 45 degrees apart, the modulated voltages appearing in the plate circuits

of 301 and 302 would be 90 degrees apart by virtue of the frequency multiplication of the phase shift. The differential modulation applied by transformer 306 therefore modulates the combined output appearing in tuned circuit 304 between the 90 degree limits and either side of the mean between the 90 degree difference.

The relative amplitudes of the two voltages to be combined in any of the above circuits could be adjusted by varying the element voltages on the modulators, amplifiers or frequency multipliers as well as by the variable condenser method as shown in Figures 4 and 5.

It will be understood that there are many more possible combinations of frequency multiplication and phase shift that could be used with these circuits. For instance, in the case of Figure 5, frequency tripling could be used and R, C adjusted for 30 degrees phase shift. In this circuit the plate circuits could be combined in parallel as shown or in push-pull since this would merely change the phase of combination from 90 to 270 degrees which is immaterial as far as distortion and depth of modulation are concerned, but might improve the efficiency of the frequency multipliers. Another alternative for the double modulator type would be the use of the phase shifting circuit employed in Figure 3 and operate the modulators as frequency doublers. This phase shifting circuit applies a 135 degree phase shift which would be multiplied to the optimum 270 degrees.

What is claimed is:

1. In a phase modulation system the combination of a source of wave energy of carrier wave frequency, an output circuit, a pair of electron discharge devices having input electrodes and having output electrodes coupled to said output circuit, means for impressing voltage of a first phase from said source on the input electrodes of one of said devices, means for impressing voltage of a phase differing from the phase of said aforesaid voltages by about 135 degrees on the input electrodes of the other of said devices, means for producing a ratio of substantially .707 to 1 between the amplitudes of said voltages impressed on said input electrodes, and means for controlling the impedance of that one of said devices, on which voltage of the least amplitude is impressed, at signal frequency.

2. In a phase modulation system, a source of wave energy of carrier wave frequency, an output circuit, a pair of electron discharge tubes having input electrodes and having output electrodes coupled to said output circuit, means for operating said tubes as frequency multipliers, means for impressing voltage of a first phase from said source on the input electrodes on one of said tubes, means for impressing voltage of a phase differing from the phase of said aforesaid voltage by about 135 degrees from said source on the input electrodes on the other of said tubes, means for producing a ratio of substantially .707 to 1 between the amplitudes of said voltages impressed on said input electrodes and means for modulating the impedance of that one of said tubes, on which voltage of the least amplitude is impressed, at signal frequency.

3. A system as recited in claim 2 wherein the impedance of the other of said tubes is modulated at signal frequency and in phase displaced relation with respect to the impedance modulation of said one tube.

4. In a phase modulation system, an oscillation generator of the substantially constant frequency

electron discharge tube type, a pair of electron discharge devices each having input electrodes and output electrodes, one of said devices at least having an additional control electrode, a high frequency circuit including phase displacing means coupling the input electrodes of one of said devices to said generator, a high frequency circuit including amplitude reducing means coupling the input electrodes of the other of said devices to said generator, a high frequency output circuit connected to the output electrodes of said devices, and means connected with said additional control electrode and the cathode of said one of said devices only for impressing modulating potentials on the additional control electrode and cathode of said one of said devices only.

5. In a phase modulation system, an oscillation generator of the substantially constant frequency electron discharge tube type, a pair of electron discharge devices each having input electrodes and output electrodes, one of said devices at least having an additional control electrode, a high frequency circuit including phase displacing means coupling the input electrodes of one of said devices to said generator, a high frequency circuit including amplitude regulating means coupling the input electrodes of the other of said devices to said generator, an output circuit tuned to a harmonic of the frequency of the oscillations generated by said generator connected to the output electrodes of said devices, and means connected with said additional con-

10 trol electrode and the cathode of said one of said devices only for impressing modulating potentials on the additional control electrode and cathode of said one of said devices only.

15 6. The method of phase modulating wave energy at signal frequency which includes the steps of, producing voltages of frequencies related harmonically to the frequency of said wave energy and of different phases and amplitudes, varying the amplitude of said produced voltage having the smallest amplitude in accordance with modulating potentials, and combining said voltage the amplitude of which is varied at signal frequency with another of said produced voltages the amplitude of which has not been so varied to produce a resultant voltage of varying phase.

20 7. The method of phase modulating wave energy in accordance with signalling potentials which includes the steps of, producing voltages characteristic of said wave energy, relatively phase displacing the said produced voltages, producing a difference in the respective amplitudes of said produced voltages, relaying said phase displaced voltage having the greatest amplitude, amplitude modulating only said phase displaced voltage having the smallest amplitude in accordance with signal potentials, and combining the relayed voltage with the amplitude modulated voltage to produce wave energy modulated in phase at signal frequency.
